UNITED STATES PATENT OFFICE.

EDWARD L. HAUCK, OF INDIANAPOLIS, INDIANA.

DESIGN FOR A JAR OR BOTTLE COVER BLANK.

SPECIFICATION forming part of Design No. 30,613, dated April 25, 1899.

Application filed March 31, 1899. Serial No. 711,289. Term of patent 14 years.

To all whom it may concern:

Be it known that I, EDWARD L. HAUCK, a citizen of the United States, residing at Indianapolis, in the county of Marion and State 5 of Indiana, have invented and produced a certain new Design for a Jar or Bottle Cover Blank, of which the following is a specification.

Referring to the accompanying drawings, which form a part of this specification, Figure 1 is a top or plan view of my design, and Fig. 2 an edge view thereof, these two views being deemed necessary to fully illustrate my design.

5 The leading feature of my design consists of a circular disk and a marginal lug projecting out therefrom, said lug being a mutilated circular disk described with a radius approximately one-third of the length of the radius of the large disk, the mutilated portion being outermost of the lug and consisting of an in-

ward curve, which is the arc of a circle of approximately the same radius as the large disk, the centers of curvatures of all of the circular curves being in the same straight 25 line.

A is the disk, which is circular in its general contour, and B is the marginal lug, which is integral with the disk and of the same thickness therewith. Its sides $a b a b$ are described 30 from the same center and the side $b b$ from a center outside at x.

What I claim is—

The design for a jar or bottle cover blank, substantially as herein shown and described. 35

In witness whereof I have hereunto set my hand and seal, at Indianapolis, Indiana, this 28th day of March, A. D. 1899.

EDWARD L. HAUCK. [L. S.]
